CLAIM

The ornamental design for an elastic fabric arm and chest exercise device, as shown and described.

DESCRIPTION

FIG. 1 is a top plan view of the elastic fabric arm and chest exercise device showing the arm cuffs in an expanded position;

FIG. 2 is a side elevation view thereof, the opposite side view being identical thereto;

FIG. 3 is a bottom view thereof;

FIG. 4 is a view of one end of FIG. 1;

FIG. 5 is a view of an opposite end of FIG. 1;

FIG. 6 is a top plan view thereof showing the arm cuffs in a collapsed position;

FIG. 7 is an end elevation view of one end of FIG. 6;

FIG. 8 is a side elevation view of FIG. 6;

FIG. 9 is an end elevation view of the opposite end of FIG. 6;

FIG. 10 is a bottom plan view of FIG. 6; and,

FIG. 11 is a perspective view of FIG. 1.
